TEMPERATURE ACTUATED CIRCUIT
CLOSING DEVICE

Harry Spiro, San Francisco, Calif.

Application November 30, 1932
Serial No. 645,018

3 Claims. (Cl. 200—142)

This invention relates to a temperature actuated circuit closing mechanism intended for use in conjunction with automatic fire alarm sounding or signalling devices, and the like, and particularly to a modified or improved form of the mechanism shown in my former Patent Number 1,868,925, entitled "Temperature actuated circuit closing device" issued July 26th, 1932.

The temperature actuated circuit closing device disclosed in Patent Number 1,868,925, briefly stated, comprises a two strand cable of any desired length in which the strands are insulated with relation to each other. Insulation is removed from the cable at spaced intervals to expose the strands and tubular sleeves are inserted in the cables at the points where the insulation has been removed. Each sleeve supports a circuit closing device which is normally held out of contact with the exposed portions of the strands by means of a fusible metal, hence if the metal is subjected to a sufficiently high temperature produced by a fire or the like, the metal will melt or fuse, the circuit closing device is released and as such will engage the exposed portions of the wires and automatically close a circuit which will cause the sounding of an alarm, etc.

The device disclosed in the patent just referred to is simple, cheap to manufacture, it is easy to install and functions to perfection, but it lacks one function which is desirable in certain installations, to-wit, that of opening the circuit or of automatically restoring itself for further operation after a fire has been extinguished.

The desirability of a self-restoring device will be better understood when it is considered that cables provided with circuit closing devices of the character described are often strung between the joists and between the wall spaces of buildings, and other places which are not readily accessible, hence if the devices are not self-restoring it is necessary, after a fire has been extinguished, to pull out one or more of the cables to reset or re-place one or more of the circuit closing devices as one or more may have functioned when the fire started.

The object of the present invention is to generally improve and simplify the construction and operation of circuit closing devices of the character described, and in particular to provide a circuit closing device which is self-restoring when a fire has been extinguished.

An improved form of the circuit closing mech-

anism is shown by way of illustration in the accompanying drawing, in which—

Fig. 1 is a perspective view of a cable showing a plurality of circuit closing devices attached thereto.

Fig. 2 is a perspective view of the circuit closing device.

Fig. 3 is an enlarged cross section taken on line III—III of Fig. 5.

Fig. 4 is a plan view of the circuit closing device shown in Fig. 2.

Fig. 5 is a longitudinal section taken on line V—V of Fig. 3, showing the circuit closing device attached to a cable.

Fig. 6 is a section similar to Fig. 5 showing a modified form of the circuit closing device.

Fig. 7 is a cross section taken on line VII—VII of Fig. 6.

Fig. 8 is a longitudinal section showing another modified form of the circuit closing device.

Fig. 9 is a cross section showing the device of Fig. 8 applied to a cable.

Fig. 10 is a diagrammatic view showing the cable connected with a source of current supply, said view also showing one of the circuit closing devices on the cable.

The circuit closing device forming the subject matter of the present application is of the thermostatic type, and more specifically stated consists of two strips of metal, or other material having varying coefficient of expansion. The two strips of metal, or other material, when secured with relation to each other and having different coefficient of expansion will flex or bend in one direction or the other when subjected to temperature variations, and this principle is relied upon in the structure herein disclosed.

In Figs. 2 to 5, inclusive, a circuit closing device is shown which is constructed of two sheets of metal soldered, riveted, or otherwise secured with relation to each other. The plates or strips forming the metal have a shape substantially such as shown in Fig. 2, one section of metal being indicated at 2 and the other at 3. The upper central portion is cut along the lines indicated at 4, 5 and 6 to form a flexible tongue or arm which is adapted to bend inwardly when subjected to an increasing temperature. One end of the tongue or arm, or that indicated at 7, is formed integral with the metal sheets 2 and 3 while the other end 6 is free to move and this end carries a contact member 8, see Figs. 3 and 5, which is adapted to move into engage-

110

ment with the strands 9 and 10 of the cable generally indicated at A.

This cable may be made of any suitable length and a number of circuit closing devices will be applied thereto, as indicated at B see Fig. 1. A two strand cable is employed, the strands being indicated at 9 and 10. These strands are separated and are embedded in insulating material, such as shown at 11, at suitable intervals; for instance, approximately every foot or so. The insulating material is removed from the cable, as indicated at 12, that is, just sufficient insulating material is removed to expose the upper surfaces of the wire strands 9 and 10. The circuit closing device is then applied and secured in position so as to cover the portion of the cable from which the insulation has been removed, and in this position the free end of the tongue 6 carrying the circuit closing member 8 will engage with the strands when subjected to sufficient temperature.

The device shown in Fig. 2 may be referred to as a bi-metallic sleeve as it is sleeve-like in shape when applied, and it furthermore is constructed of two superposed sheets of metal or the like, such as indicated at 2 and 3. In actual operation the superposed sheets of metal 2 and 3 are pressed into a substantially channel-shape, as shown in Fig. 2, and a thermostat tongue is then cut. After the insulation has been removed from the cable at suitably spaced intervals, the channel-shaped sleeves are applied and bent around the cable as shown in Fig. 3, and the sleeves may be further secured by crimping the ends as indicated at 14, see Fig. 5. This manner of securing the sleeves, together with the thermostat arms or tongues carried thereby, is exceedingly simple and one after another can be rapidly applied either by hand or machine operation. It is, however, essential that they be properly positioned with relation to the exposed portions of the strands 9 and 10 so that the contact bar or member 8 carried by the free end of the tongue will engage the exposed portions of the strands when a circuit is to be closed.

The circuit closing device may be employed for any suitable purpose, but it is particularly intended for sounding an alarm or giving a signal in case of a fire. Cables of this character are strung throughout a building, a warehouse, or whatever the case may be. All cables will be connected with a battery 15, or any other suitable source of current supply, and in the circuit will be placed a bell 16 or any other alarm sounding or signalling device. If a fire is started, the temperature in the immediate vicinity will rapidly increase and tongue or arm 6 will bend inwardly so as to bring the contact member 8 in engagement with the exposed portions of the strands. The moment a contact is made a circuit is closed through the battery and the alarm mechanism 16 and an alarm will thus be sounded, and if the fire is successfully extinguished, the temperature will gradually drop or return to normal and the tongue or tongues on the circuit closing devices will gradually return to normal position. Hence, they are self-restoring after a fire has been extinguished and the circuit through the alarm mechanism is thus automatically broken. This is an obvious advantage when comparison is made with my former patent referred to, as it does not require re-setting of the circuit closing devices as previously described.

In Figs. 2 to 5, a circuit closing device has been disclosed which is constructed entirely of a bi-metallic sleeve. This, however, is not essential as the sleeve itself may be made of any ordinary metal, or other suitable material. The 80 movable tongue or arm, however, must be made of bi-metallic material as it is the bi-metallic material which insures movement of the arm.

In Figs. 6 and 7 a sleeve 18 is disclosed. This may be made of any ordinary metal, or 85 other suitable material, but the tongue or arm indicated at 19 is constructed of a bi-metallic strip. The free end is adapted to move with relation to the exposed strands to close a circuit therethrough but the other end is riveted, 90 soldered, welded, or otherwise secured to the sleeve as indicated at 20.

In Figs. 8 and 9, a sleeve is employed which is made in two sections, such as indicated at 21 and 22. The upper section 22 is made of a bi-metallic material and the movable arm or tongue 23 is formed integral therewith in a manner similar to that illustrated in Fig. 2. The lower half of the sleeve indicated at 21 may be constructed of any ordinary material similar to 100 the sleeve shown at 18 in Fig. 6. The sleeve 22 is first applied to the cable and then the sleeve 21, and as this is bent over the sides of the sleeve section 22 and the ends of both sleeves are crimped to the cable in a manner similar to 105 that shown at 14 in Fig. 5, the two sections will be rapidly secured.

Plainly speaking, the sleeve may be made throughout of a bi-metallic material, as shown in Figs. 2 to 5; it may be made partially of 110 bi-metallic material and partially of other material as shown in Figs. 8 and 9, or it may be constructed entirely of other material as shown in Fig. 6, but it is essential regardless of construction of the sleeve that the tongue or arm 115 be made of the bi-metallic metal having different coefficient of expansion as the arm functions as a thermostat to automatically make or break an electric circuit.

It is also desirable that the arm shall be 120 formed integral with the sleeve, as shown in Figs. 2 and 3, or form a part thereof as shown in Fig. 6. By arranging the thermostat arm in this manner it will be heated just as rapidly as the sleeve and part of the heat will also be 125 derived by conduction from the sleeve. It will thus be sensitive and will act rapidly when the temperature increases. The contact member 8 should preferably be sharp so as to cut into the surface of the exposed strands 9 and 10, thereby 130 insuring a good contact; that is, a cable provided with circuit closing devices of this character may be installed for months or years before a fire may occur and during that period the exposed surfaces of the strands may become 135 more or less oxidized or coated, hence if the contact member is sharp such coating will be cut through and a good contact insured.

While certain features of the present invention are more or less specifically described, I 140 wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. An electric current carrying flexible cable comprising a pair of conductors enclosed in in- 150

sulating material and insulated with relation to each other, a portion of said insulating material being removed to expose the conductors, an elongated sleeve enclosing the exposed portions 5 of the conductors, said sleeve being constructed of two layers of material having different coefficient of expansion, a thermostatic arm forming a portion of the sleeve and formed integral therewith, one end of the arm being free to move 10 inwardly toward the exposed portions of the conductors when subjected to a predetermined temperature, and a contact member on the free end of the thermostatic arm and engageable with the conductors when the thermostatic arm 15 is actuated.

2. An electric current carrying flexible cable comprising a pair of conductors enclosed in insulating material and insulated with relation to each other, a portion of said insulating material 20 being removed to expose the conductors, an elongated sleeve enclosing the exposed portions of the conductors, said sleeve being constructed of two layers of material having different coefficient of expansion, a thermostatic arm forming 25 a portion of the sleeve and formed integral therewith, one end of the arm being free to

move inwardly toward the exposed portions of the conductors when subjected to a predetermined temperature, and a contact member on the free end of the thermostatic arm and engageable with the conductors when the thermostatic arm 80 is actuated, said contact member presenting a sharp edge to insure a good contact when in engagement with the conductors.

3. An electric current carrying flexible cable comprising a pair of conductors enclosed in insulating material and insulated with relation to each other, a portion of said insulating material being removed to expose the conductors, an elongated sleeve enclosing the exposed portions 85 of the conductors, such sleeve having an elongated opening formed therein, a thermostatic arm disposed in said elongated opening and forming a closure therefor, means securing one end of the arm to the sleeve, said means leaving the other end of the arm free, and a 90 contact member on the free end of the arm and engageable with the exposed portions of the conductors to close an electric circuit through the conductors when the arm is subjected to a predetermined temperature. 95
